UNITED STATES PATENT OFFICE.

CORNELIUS VAN GEMERT, OF ALBIA, IOWA.

DESIGN FOR A GAME-BOARD.

52,862.

Specification for Design.

Patented Jan. 7, 1919.

Application filed October 19, 1918. Serial No. 258,902. Term of patent 14 years.

To all whom it may concern:

Be it known that I, CORNELIUS VAN GEMERT, a citizen of the United States, residing at Albia, in the county of Monroe and State of Iowa, have invented a new, original, and ornamental Design for a Game-Board, of which the following is a specification, reference being had to the accompanying drawing, forming part thereof.

The figure is a face or plan view of a game board embodying my design.

I claim:

The ornamental design for a game board, as shown.

CORNELIUS VAN GEMERT.

Witnesses:

J. A. CANNING,
V. D. WELSH.
